UNITED STATES PATENT OFFICE.

CLARENCE M. DAVIS, OF CAPE MAY, NEW JERSEY.

VELOCIPEDE.

1,296,931.

Specification of Letters Patent. Patented Mar. 11, 1919.

Application filed September 10, 1918. Serial No. 253,448.

To all whom it may concern:

Be it known that I, CLARENCE M. DAVIS, a citizen of the United States, and a resident of Cape May, in the county of Cape 5 May and State of New Jersey, have invented new and useful Improvements in Velocipedes, of which the following is a specification.

This invention relates to velocipedes.

10 An important object of the invention is to provide in a velocipede a means whereby the driving mechanism may be at will maintained in a state of rest with respect to the power delivering traction wheel.

15 A further object of the invention is to provide in a velocipede a means whereby an opposite rotative movement of the driving mechanism with respect to the rotation of the power delivering traction wheel may be 20 utilized to produce a breaking effect upon the rear wheels.

25 A further object of the invention is to provide in a velocipede a pair of double acting oppositely influenced clutches, one of which is oppositely actuated upon the rotation of the driving mechanism in a given direction, the other being actuated upon the rotation of the driving mechanism in an opposite direction.

30 A further object of the invention is to provide in a velocipede a means whereby the several clutches employed therein may be retained in a normal disengaged position with respect to the several co-acting elements in the absence of transmission of power to the driving mechanism.

35 A further object of the invention is to provide a velocipede of the above mentioned character which is strong, durable and reliable in operation.

40 Other objects and advantages of the invention will be apparent during the course of the following description taken in connection with the accompanying drawings.

45 In the drawings, forming a part of this specification and in which like numerals are employed to designate like parts throughout the same,

Figure 1 is a side elevation of a velocipede 50 embodying my invention,

Fig. 2 is a central longitudinal sectional

view of a clutch mechanism associated with the power delivering traction wheel,

Fig. 3 is a transverse sectional view taken on line 3—3 of Fig. 2, 55

Fig. 4 is a transverse sectional view of Fig. 2 taken on line 4—4,

Fig. 5 is a transverse sectional view of Fig. 2 taken on line 5—5,

Fig. 6 is an edge elevation of a clutch 60 member,

Fig. 7 is a side elevation of a clutch member showing the relative position of the same with respect to its co-operating clutch element, 65

Fig. 8 is a fragmental view of a clutch element retainer,

Fig. 9 is a longitudinal vertical sectional view of the head of the velocipede,

Fig. 10 is a transverse sectional view 70 taken on line 10—10 of Fig. 9,

Fig. 11 is a horizontal sectional view taken on line 11—11 of Fig. 9,

Fig. 12 is a top plan of a rear hub mechanism, the hub being shown in section, 75

Fig. 13 is a similar view, the hub being shown partly in plan and partly in section,

Fig. 14 is a transverse sectional view taken on line 14—14 of Fig. 12,

Fig. 15 is a transverse sectional view 80 taken on line 15—15 of Fig. 12, and,

Fig. 16 is a detail view of a Bowden wire.

In the drawings, wherein for the purpose of illustration is shown a preferred form of 85 my invention, the numeral 10 indicates the main frame of a velocipede constructed

preferably of hollow tubing connected at its upper end to a head 11. Within the head 11 there is arranged a vertical shaft 12 which terminates in a pair of forks 13

providing a shoulder 14 having engagement with the head 11 as clearly shown in Fig. 9. The shaft 12 is provided with an adjustable shoulder 15 co-operating with the shoulder 14 to retain the shaft 12 within the head 11. The shaft 12 is provided centrally with a bore 16 having a communicating slot 17. Within the bore 16 there is 90

arranged a reciprocating rod 18 which is provided with a stud 19 projected through the slot 17. Within the bore 16 there is 95 arranged a reciprocating rod 18 which is provided with a stud 19 projected through the slot 17. This stud is adapted for co- 100

- operation with an arm 20 which encircles the shaft 12, the arm 20 being pivotally connected to a lug 21 carried within the head 11 by means of a pin 22. To the arm 20 there is connected a second arm 23 which in turn is connected to the twisted end 24 of a Bowden wire 25 having diverging ends 26, the twisted end 24 being arranged within the frame 10 as clearly shown in Fig. 9.
- 10 In order to retain the arm 20 together with the reciprocating rod 18 normally in the position shown in Fig. 9 there is provided a coil spring 27, one end of which engages the lower side of the head 11, the other end being retained in engagement with the arm 20. Upon the head 11 there is arranged a closure 28 which incloses the several elements arranged within the head, the closure being secured in position by means of rivets 29
- 15 or the like having engagement with lugs 30 preferably formed integral with the head 11. Within the lower ends of the fork member 13 there is journaled a spindle 31 having connected at its ends a pair of crank arms 32. Upon the spindle 31 there is rotatably mounted a hub 32' comprising a pair of receivers 33 and 34. In proximity to the receiver 33 there is arranged a disk 35 provided with a flange 36 having engagement with the inner periphery of the receiver 33 as clearly shown in Fig. 2. The flange 36 by means of frictional engagement serves not only as a means for retaining the disk 35 in proper related position with respect to the receiver 33 but also as a means for retaining the ends of the spokes 37 of the power delivering traction wheel 38. In proximity to the receiver 34 there is arranged a ring 39 which is provided with a flange 40, the flange 40 functioning identical with the flange 36 of the disk 35. The disk 35 is provided upon its outer face with an annular groove 41 adapted for the reception of lugs 42 carried at the ends of arcuate shaped clutch segments 43 which are arranged within a rotating housing 44.
- 20 Through the spindle 31 there is passed a pin 45 having its ends projected through elongated slots 46 provided by the housing 44. In order to normally retain the segments 43 in their respective positions as shown in Fig. 3 there is provided a pair of elongated springs 47 and 48, the spring 47 being connected to the pin 45 as shown at 25 49, the other end of the spring being secured to the housing 44 as shown at 50. The spring 48 likewise has one of its ends connected to the pin 45 as shown at 51 and its other end connected to the housing 44 as shown at 52. Upon the shaft 31 there is rotatably mounted a disk 53 which is provided with an arm 54 and an annular groove 55, the groove 55 being adapted for the reception of lugs 56 carried by the segments

57 which are arranged within a housing 58. Within the spindle 31 there is arranged a pin 59 having its ends projected through openings 60 provided by the housing 58. In order to retain the segments 57 normally in the position shown in Fig. 4 there is provided a pair of springs 61 and 62, the spring 61 being connected at one end to the pin 59 as shown at 63 while the other end is connected to the housing 58 as shown at 64. The spring 62 is likewise connected at one end thereof to the pin 59 as shown at 65 and has its other end connected to the housing 58 as shown at 66.

The frame 10 is provided with a transversely disposed axle 67 carrying a pair of 80 wheels, one of which is indicated as a whole by the numeral 68. Each of the wheels 68 comprises a hub 69 provided with sockets 70 and 71. In proximity to the socket 70 there is arranged a disk 72 provided with a flange 85 73. The flange 73 serves not only as a means for frictionally engaging the inner face of the socket 70 thereby retaining the disk 72 in position but also as a means for retaining the ends of the spokes 74 of the wheels 68. Within the socket 71 there is arranged an annular ring 75 which serves as a means for retaining in position the ends of the spokes 74. The ring 75 carries a flange 76 which is provided with an inner bevel face 77 adapted for engagement with the cone shaped end 78 of a brake plug 79. The brake plug 79 is provided at its ends with a pair of cam lugs 80 and 81 having engagement respectively with a lug 82 carried by the axle 67 and a portion of the frame 10 as shown at 83, the axle 67 and the lug 83 being carried by the frame 10. To the brake plug 79 there is connected an arm 84 which in turn is connected to the end 26 of the Bowden wire 25.

In use, when the spindle 31 is rotated in the direction of the arrow *f* the ends of the pin 45 moves within the slots 46 and consequently the pin is partially rotated with respect to the housing 44 whereupon pressure is exerted by the pin 45 upon those ends of the arcuate shaped clutch segments 43 opposite the ends thereof which carry the lugs 42. As a result of this exertion of pressure each of the arcuate shaped clutch segments 43 tend to rotate about their respective lugs 42 whereupon the outer faces of the lugs 42 frictionally engage the larger circumferential face within the groove 41 while the opposite faces of the lugs 42 frictionally engage the smaller circumferential face within the groove 41 thereby locking the spindle 31 with respect to the hub 32' whereupon forward rotary movement is transmitted to the power delivering traction wheel. The relative position of one of the arcuate shaped clutch segments 43 and its lug 42 with respect to the pin 45 when the spindle 31 is ro-

tated in the direction of arrow *f* is clearly illustrated in Fig. 7. When the spindle 31 is rotated in the direction of the arrow *f* the pin 59 is brought to bear against these ends 5 of the segments 57 at which the lugs 56 are carried and consequently the segments 57 are not moved from their normal position as shown in Fig. 4. Since the segments 57 are not moved from their normal position 10 when the spindle 31 is rotated in the direction of arrow *f* no locking effect between the lugs 56 and the faces of the groove 55 is produced. When the spindle 31 is at rest with respect to the rotating hub 32' regardless of 15 whether it be rotating in a forward or backward direction the segments 43 and 57 together with their respective lugs 42 and 56 are retained in the positions shown in Figs. 3 and 4 respectively by means of springs 47 and 48 engaging segments 43 and springs 61 and 62 engaging segments 57. Since these segments are retained normally in the position shown in Figs. 3 and 4 when the spindle 31 is at rest no locking effect is produced 20 between the spindle 31 and the hub 32' or between the spindle 31 and the disk 53. When it is desired to create a braking effect upon the rear walls 68 regardless of whether the power delivering traction wheel 38 is moving forward or is at rest, the spindle 31 is 25 partially rotated in the direction of the arrow *b* shown in Fig. 2. As a result of the backward movement of the spindle 31 the pin 59 is brought to bear upon those ends of 30 the arcuate shaped clutch segments 57 opposite the ends to which the lugs 56 are secured whereupon the segments 57 tend to rotate about the lugs 56 causing the outer faces of the lugs to engage the larger peripheral wall 35 of the groove 55 while the inner faces of the lugs engage the smaller peripheral wall of the groove 55, thereby producing a locking effect between the spindle 31 and the disk 53. As a result of the locking effect produced 40 between the disk 53 and the spindle 31 the arm 54 is moved with the partially rotating spindle 31 in which instance the reciprocating rod 18 is moved downwardly against the influence of the spring 27. The 45 downward movement of the reciprocating rod 18 necessarily moves the arm 23. Upon the movement of the arm 23 a similar movement is transmitted to the arm 84 through the instrumentality of the Bowden wire 25. As a result of the movement of the arm 84 50 the cam 81 co-acting with the frame 10 at 83 forces the cone shaped member 78 into engagement with the face 77 of the flange 76, thereby imparting a braking action to the 55 wheels 68. When the spindle 31 is partially rotated in the direction of the arrow *b* the pin 45 exerts pressure upon the ends of the arcuate shaped clutch segments 43 in proximity to the lugs 42 in which instance the

segments 43 retain their respective normal 65 position as shown in Fig. 3 in which position the lugs 42 remain disengaged from the walls of the groove 41. When the spindle 31 is moved forward in the direction of the arrow *f* the segments 57 through the instrumental- 70 ity of the spring 62 assume the position shown in Fig. 4 whereupon the lugs 56 are disengaged from within the groove 55 and the arm 23 through the influence of the spring 27 is moved to the position shown in 75 Fig. 9, thereby relieving the braking action upon the rear wheel 68.

It is to be understood that the form of my invention herewith shown and described is to be taken as a preferred example of the 80 same, and that various changes in the shape, size and arrangement of parts may be resorted to without departing from the spirit of the invention or the scope of the subjoined claims. 85

Having thus described my invention, what I claim as new and desire to secure and protect by Letters Patent of the United States, is:

1. The combination with a velocipede 90 having driving mechanism associated with the power delivering traction wheel thereof, of braking mechanism associated with the rear wheel of the velocipede, means whereby the braking mechanism may be actuated 95 upon the opposite rotative movement of the driving mechanism with respect to the rotation of the power delivering traction wheel.

2. The combination with a velocipede 100 having driving mechanism associated with the power delivering traction wheel, of a brake mechanism associated with each of the rear wheels of the velocipede, a clutch carried by said driving mechanism to deliver 105 rotation to said traction wheel upon the rotation of said driving mechanism in one direction, a second clutch carried by said driving mechanism, the second named clutch being actuated upon opposite rotative movement of the driving mechanism with respect to the rotation of the power delivering traction wheel, and means connecting said braking mechanism with the second named 110 clutch whereby the braking mechanism may 115 be actuated upon the movement of the second named clutch.

3. The combination with a velocipede, of a braking mechanism applied to each of the rear wheels thereof, a pair of clutches associated with the power delivering traction wheel, rotatable driving mechanism, means for locking one of said clutches with respect to said driving mechanism upon the rotation of the same in one direction whereby rotation is imparted to said power delivering traction wheel, and means for locking the other of said clutches with respect to said 120 125

- driving mechanism upon the opposite rotation of the same, means connecting said braking mechanism and said other clutch whereby said braking mechanism may be actuated upon the actuation of the clutch connected therewith.
4. The combination with a velocipede, of a pair of clutches associated with the power delivering traction wheel, driving mechanism, means for locking the power delivering traction wheel, driving mechanism and one of said clutches upon the rotation in one direction of said driving mechanism, means for releasing the locking engagement between said power delivering traction wheel clutch and driving mechanism upon the rotation in an opposite direction of said driving mechanism, a brake mechanism associated with the rear wheels of the velocipede, and actuatable means including said other clutch for operating said brake mechanism, the last named means being actuated upon the opposite rotation of said driving mechanism.
5. The combination with a velocipede, of a braking mechanism associated with the rear wheels thereof, a shaft journaled within the power delivering traction wheel, said shaft being free to rotate with respect to said traction wheel, and means actuating said braking mechanism upon the opposite rotative movement of said shaft with respect to the power delivering traction wheel.
6. The combination with a velocipede, of a braking mechanism associated with the rear wheels thereof, actuating means associated with the traction wheel, said actuating means being free to rotate with respect to the traction wheel, means for locking the traction wheel with respect to the actuating means upon the rotation of the actuating means in one direction, means for unlocking the power delivering traction wheel from the actuating means upon the rotation of the actuating means with respect to the power delivering traction wheel, and means actuatable simultaneously with said unlocking means for actuating said brake mechanism, the last named means being dependent for its operation upon the opposite rotation of the actuating means with respect to the power delivering traction wheel.
7. The combination with a velocipede, of a brake mechanism associated with the rear wheels thereof, actuating means for the power delivering traction wheel, a clutch carried by said actuating means and operated upon the rotation of said actuating means in one direction to lock the power delivering traction wheel with respect to the actuating means, a second clutch carried by

said actuating means and actuated upon the opposite rotative movement of said actuating means to produce a braking effect upon the rear wheels through said brake mechanism. 65

8. The combination with a velocipede, of a brake mechanism associated with the rear wheels thereof, actuating means for the power delivering traction wheel, a clutch carried by said actuating means and operated upon the rotation of said actuating means in one direction to lock the power delivering traction wheel with respect to the actuating means, a second clutch carried by 75 said actuating means and actuated upon the opposite rotative movement of said actuating means to produce a braking effect upon the rear wheels through said brake mechanism, and means for retaining said clutch 80 mechanism in normal position.

9. The combination with a velocipede, of a brake mechanism associated with the rear wheels thereof, power delivering means associated with the power delivering traction 85 wheel, the power delivering traction wheel being loosely mounted upon said power delivering means, means for locking the power delivering traction wheel with respect to the power delivering means upon the rotation 90 of the power delivering means in a given direction, a rotative clutch member arranged upon said power delivering means and connected with said braking mechanism, means for locking said power delivering means 95 with respect to said clutch member upon the rotation of said power delivering means in a given direction whereby a braking effect will be imparted to the rear wheels through 100 said braking mechanism, and means for returning the clutch element to its normal position.

10. The combination with a velocipede, of a brake mechanism associated with the rear wheels thereof, power delivering means associated with the power delivering traction wheel, the power delivering means being free to rotate with respect to the power delivering traction wheel, a clutch for locking the power delivering wheel with respect to the power delivering means upon the rotation of the power delivering means in one direction, a second clutch, means for locking the second named clutch with respect to the power delivering means upon opposite 115 rotation of the power delivering means, a flexible cable connecting said brake mechanism and second named clutch whereby a braking effect will be imparted to the rear wheels upon the action of the second named 120 clutch.

CLARENCE M. DAVIS.
